HYDRAULIC TURBINE

Charles R. Martin, Wauwatosa, Wis., assignor to
Allis-Chalmers Manufacturing Company, Milwaukee,
Wis., a corporation of Delaware

Application November 20, 1930
Serial No. 496,864

6 Claims. (Cl. 253—117)

This invention relates in general to the art of hydraulic power installations and relates more specifically to improvements in the construction and formation of concrete inlet flumes and spiral casings thereof for hydraulic turbines using open and closed flumes.

It has been the practice in hydraulic power installations to provide the floor and ceiling of closed type of inlet flumes with opposed concrete truncated cone supports for the different turbine elements, which project from the floor and from the ceiling to an extent and in a manner to cause a non-uniform velocity of flow of the water in the inlet flume and to cause the presence of dead water pockets adjacent the base marginal portions of the supporting "cones" and eddies resulting from said pockets, all of which are undesirable features. These objectionable features are eliminated according to this invention and the function of the truncated cone support retained by suppressing the cones. This is accomplished by filling in the side walls of each cone with concrete to provide a superposed suppressed surface or substantially continuous ramp surface 25 face the marginal portions of which extend to the side walls of the inlet flume or double spiral casing and the forward marginal portions thereof intersect the more or less inclined plane surfaces of the floor and ceiling along points farther away 30 from the turbine shaft or in other words nearer the mouth of the spiral casing.

A more specific object of the invention, therefore, is to provide a double spiral concrete casing inlet flume having opposed, substantially continuous ramp surfaces of concrete in the floor and ceiling, surrounding the guide casing receiving openings whereby dead water pockets and eddies ahead of the runner resulting from said pockets are eliminated, and the spiral casing may therefore be made with cross-sectional areas such that the water entering the spiral casing will be gradually accelerated to the required flow in the guide casing and all sudden increases in velocity eliminated. The substantially continuous water ramps gradually increase the velocity of the water within the spiral casing and prevent sudden changes of velocity within the casing and confine the sudden changes of velocity to the points where the water leaves the spiral casing and enters the guide casing.

The formation of the ramps in the inlet flume or spiral casing as contemplated by this invention, further provides additional masses of concrete for properly supporting the turbine ele-

ments and very materially augments the stability of operation of the hydraulic power unit.

The ramp surface further acts as a splitter for the incoming water to divide the water flow and tends to eliminate the objectionable pulsating or pendulum swing of the entering water.

The four primary advantages to be gained in a hydraulic power installation having the improved concrete spiral casing as a portion of its inlet flume, the inlet flume comprising the spiral casing itself and the intake 6 or 26, are first, increased efficiency under the same conditions of head and speed; second, increased power; third, smoother operation of the power unit and fourth, a reduction in the tendency of the water to pit the various parts of the turbine, such as the discharge ring, the turbine runner and the guide vane tips. All of these effects are inter-related and it is contended that the suppression of the supporting cones will eliminate some of the contributory causes of loss in power and in efficiency, of excessive vibration and of pitting of the turbine parts which lie within the turbine water passages.

Other objects and advantages of the present invention will become apparent from a reading of the specification and of the drawings forming a part thereof on which like or the same numerals are used to designate the same or similar parts throughout the various views.

Fig. 1 is a central vertical section through a hydraulic power installation of the vertical shaft turbines, employing one form of spiral inlet casing, constructed according to this invention.

Fig. 2 is a longitudinal horizontal section taken substantially along line II—II of Fig. 1, looking in the direction of the arrows.

Fig. 3 is a perspective view of a portion of the spiral inlet casing shown in Fig. 1 and as seen looking in the direction of line II—II of said figure.

Fig. 4 is a central vertical section through another hydraulic power installation, also of the vertical shaft type, employing a modified form of spiral inlet casing, constructed according to this invention.

Fig. 5 is a longitudinal horizontal section taken substantially along line V—V of Fig. 4, looking in the direction of the arrows.

Fig. 6 is a perspective view of the spiral inlet casing shown in Fig. 4 with the ceiling thereof tilted from its normal position to more clearly disclose the ceiling ramp surface.

Referring to Fig. 1 reference numeral 1 is used to designate the concrete ceiling and 2 the con-

crete floor of a concrete inlet flume, and spiral inlet casing thereof, of a hydraulic power installation especially applicable for low heads and small hydraulic turbines. 5 is the head water foundation plate of concrete and resting thereon is the concrete intake 6 of the inlet flume. A ledge 31 on intake 6 cooperates with the plate 5 to form a passage for directing head water directly into the mouth of the spiral casing. The intake 6 is horizontally divided by a pier 8 extending a substantial distance within the spiral casing of the inlet flume. Gate slots 19 are provided in the continuations of the parallel side walls 7 of the spiral casing, that are aligned with cooperating gate slots 19 in the pier 8 and in the head water foundation plate 5 to receive gates for the purpose of excluding water from the spiral casing when repairs or replacements are to be made to the power unit.

The power unit comprises a hydraulic turbine direct-connected by means of a main shaft 13 to a power transforming machine 14, such as an electric dynamo. The dynamo 14 is mounted directly on a ring of concrete formed in web 20 of concrete which forms between it and ceiling 1 a pit 17 from which access may be had to the various parts of the power unit. The hydraulic turbine is positioned directly below the dynamo 14 and is carried by a discharge ring 10 mounted upon the horizontal annular portion of the old and well known concrete truncated supporting cones, which portion is retained in the improved spiral inlet casing structure. The annular portion is positioned at a higher elevation than the head water foundation plate 5 and requires sloping of the floor to intersect the reverse spiral curved wall surfaces substantially in the plane of the said annular support portion or in the plane of the discharge ring 10 directly mounted thereon, which wall surfaces terminate in a common nose 9. Such sloped floors would be intersected by the supporting cones of the prior art power installations of the hydraulic turbine type of which the supporting cone shown in Figure 4 of the Taylor Patent 1,681,711, patented August 21, 1928, is a fair representation, substantially as disclosed by the steep side wall forming the circumferential boundary of said cone. The suppression of the prior art supporting cones by filling in with concrete to provide a superposed surface on the sloped floors of the prior art concrete inlet flumes or a substantially continuous ramp surface on said floors according to this invention takes the form as clearly shown in Figs. 2 and 3. The substantially straight or uniform slope elements of the ramp surface provide a multiplicity of paths for the various filaments of water in the spiral casing and result in uniform increases in the velocities thereof while within the spiral casing and confines sudden velocity changes to the points where the filaments leave the casing and enter the guide casing. Because of the elimination of the dead water pockets with this ramp construction, eddies resulting therefrom in the water flowing in the guide casing are eliminated and accordingly pitting of the hydraulic turbine runner 12, discharge ring 10 and guide vanes 15 is materially lessened and a more efficient energy conversion realized with the runner 12. The water after having given up most of its kinetic energy to the runner 12 flows through the draft tube 11 from which it discharges into the discharge flume or tail race 18.

The hydraulic power installation shown in Fig.

4 is especially applicable for medium heads and for hydraulic turbines that are larger than those for the installation shown in Fig. 1. The increased span of the intake 26 which corresponds to the intake 6 of the modification shown in Fig. 1 necessitates the use of a plurality of supporting piers 28 in order to properly carry the suspended ceiling 21. The intake 26 is provided with pairs of gate slots 19 arranged in series to receive gates for the same purpose stated in connection with the modification of Fig. 1.

The construction of this modified form of inlet flume and spiral casing forming a part thereof differs from the one disclosed by Figs. 1-3 in that both ceiling 21 and floor 22 are provided with substantially continuous ramp surfaces. As shown the intake 26 cooperates directly with an inclined portion of the head water foundation plate 25 to form a passage for directing water directly to the mouth of the spiral casing and therefore the degree of suppression in the ramp surface rising from the slightly inclined plane portion of the floor 22 is correspondingly less than that in the ramp surface of floor 2 of the modification disclosed by Fig. 1. The degree of suppression in the ramp surface depending from the slightly and reversely inclined plane portion of the ceiling 21 is more pronounced from that in the ramp surface of the floor 22 but is approximately equal to that in the ramp surface in the floor 2 of the spiral casing shown in Fig. 1. It will be noted, however, that the extreme rear portions which terminate in a point at the nose 29 of both the ceiling and floor ramp surfaces of the modified spiral casing shown in Fig. 4 are composed of substantially straight line elements that progress in inclination from the nose 29 as clearly disclosed by Figs. 5 and 6, whereas the corresponding portions of the ramp surface of floor 2 of the spiral casing shown in Fig. 1 are substantially flat. With the latter or modified formation of the opposed ceiling and floor ramp surfaces a spiral casing is realized in which the cross-sectional flow areas are such as to effect a gradual acceleration of the water entering the mouth of the spiral casing to the velocities of flow required in the different peripheral portions of the guide casing and this modified form of spiral casing is preferred for medium heads. Again referring to Figure 4 of the Taylor Patent 1,681,711, which shows a supporting cone having a steep side wall and which cone, as stated before, is fairly representative of the unsuppressed truncated cones of the prior art hydraulic turbine installations, the amount of fill necessary to produce this modified form of spiral inlet casing can be visualized.

The water passing through the spiral casing after having been directed by the guide vanes 15 within the guide casing impacts against the runner 12, free to rotate within the discharge ring 10, which absorbs most of its kinetic energy and then flows through the elbow draft tube 11 from which it discharges into the discharge flume or tail race 18. Gate slots 30 are provided in the tail race portion of the integral concrete setting of the shown hydraulic power installation and serve to receive the usual tail race stop logs at times required in such installations.

While the ramp surface construction or suppression of the truncated supporting cone idea has been disclosed as employed in a double spiral inlet concrete casing it is perfectly obvious that the ramp surface construction may readily be applied to and employed in the ordinary type of

single spiral concrete casing and in casings having straight end walls.

And although the principle of the invention has been shown as applied and specifically described in connection with vertical shaft hydraulic installations it is perfectly obvious that said principle may equally well be applied to horizontal shaft turbines with beneficial results.

It is also to be understood that in certain cases it may be desirable to have a ceiling ramp surface substantially as shown in Figs. 4, 5 and 6 with a cooperating completely obliterated cone surface or flat floor surface destroying the identity of the cone support as exemplified in the floor of the casings of Figs. 1 and 2 of the Taylor Patent 1,681,711. And that in some cases it may be desirable to use a ramp type of approach as shown in Figs. 1, 2 and 3 in connection with a standard open flume type of setting where the 20 turbine and its shaft are completely submerged.

It should be understood that it is not desired to limit the invention to the exact details of construction herein shown and described, for various modifications within the scope of the claims may occur to persons skilled in the art.

It is claimed and desired to secure by Letters Patent:

1. In a hydraulic power installation, a spiral casing having side walls, an end wall, and having a floor and a ceiling provided with aligned openings, a fluid intake for said casing, one of said openings serving as a fluid outlet for said casing, the other of said openings serving in the removal of a part of the installation, said floor having a suppressed cone support terminating in a projecting annular portion surrounding said floor opening, said annular portion being located at a higher elevation than the bottom for said intake and the depth of said spiral casing measured at said annular portion being less than its depth measured at its mouth, said cone support constituting a substantially continuous ramp surface which extends radially outwardly from said annular portion and intersects said side walls and said end wall, said ramp surface being formed to prevent the occurrence of dead water pockets at the base marginal portions of the cone support.

2. In a hydraulic power installation, a spiral casing having side walls, an end wall, and having a floor and a ceiling provided with aligned openings, a fluid intake for said casing, one of said openings serving as a fluid outlet for said casing, the other of said openings serving in the removal of a part of the installation, said floor and said ceiling having each a suppressed cone support terminating in a projecting annular portion surrounding its opening, said floor annular portion being located at a higher elevation than the bottom for said intake and the depth of said spiral casing measured at said annular portions being less than its depth measured at its mouth, each of said cone supports constituting a substantially continuous ramp surface extending radially outwardly from its annular portion and intersecting said side walls and said end wall, each of said ramp surfaces cooperating to eliminate dead water pockets at the base marginal portions of its cone support.

3. In an inlet flume for hydraulic turbines, a double spiral casing having substantially parallel side walls connected by a double spiral end wall, and having a floor and a ceiling provided with aligned openings, one of said openings serving as

a fluid outlet for said casing, the other of said openings serving in the removal of a part of the turbine, said floor having a suppressed cone support terminating in a projecting annular portion surrounding said floor opening, said cone support constituting a substantially continuous ramp surface which extends radially outwardly from said annular portion and intersects said end wall and substantially portions of said side walls, said ramp surface cooperating to eliminate dead water pockets at the base marginal portions of the cone support.

4. In an inlet flume for hydraulic turbines, a double spiral casing having substantially parallel side walls connected by a double spiral end wall, and having a floor and a ceiling provided with aligned openings, said floor opening serving as a fluid outlet for said casing, said ceiling opening serving in the removal of a part of the turbine, said floor and said ceiling having each a suppressed cone support terminating in a projecting annular portion surrounding its opening, each of said cone supports constituting a substantially continuous ramp surface extending radially outwardly from its annular portion and intersecting said end wall and substantial portions of said side walls, each of said ramp surfaces cooperating to eliminate dead water pockets at the base marginal portions of its cone support.

5. In a hydraulic installation, an inlet flume comprising an intake and a spiral casing, said casing having spaced side walls, an end wall and a floor, said floor being provided with a suppressed cone support, the surface of said cone support being comprised of substantially straight line elements, those of said elements extending from the top margin of the cone support toward said end end side walls extending substantially to and intersecting said end and side walls at the base margin of the cone support, the remaining line elements of said surface being longer than the shortest of said elements extending to said side walls and extending radially outwardly from the top margin of the cone support to the bottom surface of the spiral casing, and at least some of said remaining line elements extending substantially to the lower portion of the junction between said intake and said casing.

6. In a hydraulic installation, an inlet flume comprising an intake and a spiral casing, said casing having spaced side walls, an end wall and a floor, said floor being provided with a suppressed cone support, the depth of said spiral casing measured at the top margin of the cone support being less than its depth measured at its mouth, the surface of said cone support being comprised of substantially straight line elements, those of said elements extending from the top margin of the cone support toward said end and side walls extending substantially to and intersecting said end and side walls at the base margin of the cone support, the remaining line elements of said surface being longer than the shortest of said elements extending to said side walls and extending radially outwardly from the top margin of the cone support to the bottom surface of the spiral casing, and at least some of said remaining line elements extending substantially to the lower portion of the junction between said intake and said casing.
